UNITED STATES PATENT OFFICE

BURDETTE D. LA FORCE, OF ALTADENA, CALIFORNIA

SURGICAL INSTRUMENT

Application filed July 7, 1931. Serial No. 549,209.

My invention relates to the type of surgical instruments called tonsillotomes, tonsil enucleators, and tonsil snares. The primary purpose of my instrument is for the removal of faecal tonsil.

My invention has a number of different features, all of which may be utilized in their proper sequence or succession or, if desired, certain of the instruments and certain of the steps of procedure may be omitted. With my instrument I provide for what I term fixing the tonsil and utilize what I term a fixing blade. This procedure is to lift a deeply embedded and submerged tonsil from its bed and this may be effectively done by my instrument which has a very thin blade, this being adapted to undermine a tonsil and fix it in the forward end of the instrument, this securing the cap of the tonsil with all of its capsule intact. With my type of instrument having this fixing blade there is little danger of leaving any of the tonsil in the sinus tonsillaris. This fixing blade, as above mentioned, is quite thin and is designed to operate in the fenestra of a tonsillotome. Such blade is not sharp enough to sever the tissues but acts to push such tissues attached to or forming part of the tonsil to the forward end of the frame of the instrument and fix them there.

Another object and feature of my invention is the employment with the fixing blade of a hemostat blade, this being designed when thrust forward in the fenestra of the instrument to thoroughly crush the tissues. This blade is thick enough to accomplish the desired hemostasis. In my present instrument the forward end of this thick hemostat blade is preferably beveled.

Another object and feature of my invention is the provision of a cutting blade or a snare, either type of severing the tonsil being adaptable for my instrument, such blade, manifestly, having a sharp edge and the snare, if used, having a means for retracting same whereby the tonsil may be severed.

Another object and feature of my invention is the employment of what may be termed a clamping blade, this blade being brought to bear on the tonsil either before

or immediately after the severing operation, such blade being forced to the end of the fenestra and thereby clamping the tonsil so that it can be readily removed from a person's throat on removal of the instrument.

55

Another object and feature of my invention is the employment of a safety device enabling a safe method of operation and providing a device which will not allow the cutting or severing blade to be brought into action until the tonsil has been first gripped by the fixing blade. I provide this safety feature as the operations of removing tonsils are frequently performed in darkened rooms in which the only light used is fixed on the field of operation and in which there is danger that the surgeon may have his attention diverted from the instrument and not notice the position of the severing blade. Therefore, I provide a positive locking device which will prevent operation of the severing blade until the fixing blade has been properly actuated to disengage the embedded tonsil and to properly grip such tonsil. This safety locking device employs a vertical bolt or rod which passes through slots in both the fixing and the severing blade and has means for interengaging with these blades to prevent operation of the severing blade until the fixing blade has been brought into its proper 65 action and performed its function.

60

65

70

75

80

Another object and a mechanical feature of my invention leading toward its simplicity of construction and operation is a combining of the hemostat blade with certain of the other blades of the instrument, for instance, the hemostat blade may be combined and made integral with the fixing blade so that as the fixing blade is used to loosen and disengage the embedded tissues and after these are properly secured the hemostat blade will function to crush the tissues held adjacent the fixing blade. Another modification of combined blades is the combining of the hemostat blade with the severing blade in that 85 these may be made integral, or the severing blade may be constructed with the hemostat block formed thereon, in which case as the tonsil is severed the hemostat blade is brought into action to crush the tissues. The combin- 90

95

95

100

ing of blades enables the instrument to be simplified and the technique or manner of operation to be also simplified.

Another object and feature of my invention, especially when a snare is used instead of cutting blade, is that both the fixing and the hemostat blade secure the tonsil at one portion and the clamping blade at another portion. Therefore, the snare, which operates between these sets of blades effectively severs the tonsil which is firmly held from displacement. Therefore, with my construction the same frame may be utilized, substituting the different forms of blades and a snare for the knife. Where a separate knife is used it is preferable to have this attached to the hemostat blade to be actuated therewith.

Another object and feature of my invention is to provide the closure end of the fenestra of the instrument with a thin, upright projecting edge which extends above the sides of the fenestra, and such being adapted to act as a pry when pressed between the faucial tonsil and the posterior pillar of the tonsil to dislodge the tonsil from its bed and help to introduce the tonsil into and through the fenestra of the instrument.

My invention is illustrated in connection with the accompanying drawing, in which:

Fig. 1 is a side elevation of my invention partly broken away;

Fig. 2 is an enlarged longitudinal section through the fenestra end taken on the line 2—2 of Fig. 3;

Fig. 3 is a transverse section on the line 3—3 of Fig. 2 in the direction of the arrows;

Fig. 4 is a detailed longitudinal section of part of the instrument taken substantially on the line 4—4 of Fig. 5 in the direction of the arrows;

Fig. 5 is a detailed plan taken on the line 5—5 of Fig. 4 in the direction of the arrows;

Fig. 6 is a side elevation partly broken away of a portion of the instrument, showing an alternative form, using a snare;

Fig. 7 is a detailed perspective view of a combination hemostat and knife blade;

Fig. 8 is a perspective view of a combination fixing and hemostat blade;

Fig. 9 is a side elevation of the blade of Fig. 8 taken in the direction of the arrow 9.

In my instrument I provide a main frame 11 which has a horizontal bar section 12, a vertical bar 13 at one end, from which end depends a hand pistol grip type of handle 14. A sloping bar section 15 extends upwardly from the end of the horizontal portion 12 and has a horizontal bed bar 16 extending therefrom. This terminates in the fenestra end 17 of the frame. Such fenestra end has two side structures 18, an end closure 19, the sides terminating at 20, the portion 16 terminating at 21, leaving a large fenestra open-

ing 22, which opening is rectangular in plan view.

The end closure 19 has a thin rim 23 at its upper edge, this having a vertical surface on the inside. Below this surface there is a gradually beveled portion 24 engaging into a steeply beveled portion 25, and another vertical section 26. A slot 27 to accommodate the knife blade extends into or through the closure end 19 and below this there is another vertical surface 28. The inside of the rim 23 preferably has vertical corrugations and the inside of the lower beveled portion 25 has vertical corrugations. At the sides there is an upper rim 29 (note Fig. 3), below which there is a wide rib 30 and a lower rim 31, this forming an upper guide slot 32, lower guide slots 33.

The lower bar 12 is provided with an elongated slot 34, this having a wide section 35 at one end, the slot extending from the line 36 to the line 37. On the upper edge of this bar on each side of this slot there is a toothed friction surface 38 for the purpose hereinunder detailed. The vertical bar 13 is provided with a perforation 39 and at the top there is a vertical notch 40.

In the drawings, the fixing blade designated as 41 has a thin operating end 42 which has its marginal edges sliding in the upper groove 32. This blade has a vertical pressure edge 43 which presses against the inside surface of the rim 23. The portion 44 of this blade is thickened and another portion 45 is still thicker and has a threaded stem 46 formed integral therewith, this threaded end fitting in the notch 40 and having a thumb engaging end 47 to allow pressing forward of this blade. The portion 45 of the blade has a perforation 48 for a purpose hereinunder detailed. A finger operated nut 49 is threaded on the threaded stem 46 and is adapted for clamping this fixing blade in its operative position after being thrust forward to press or fix the tissues after these have been loosened from their bed.

The hemostat blade designated as 50 is quite thick and is positioned below the fixing blade. This has a thinner end portion 51 and its forward edge 52 is formed with bevels to fit against the beveled surfaces 24 and 25. This end of the hemostat blade has vertical corrugations. Such blade has a thin section 53, a downwardly extending portion 54, and a vertical end 55, which has a notch 56 therein. This notch allows fitting in a groove 57 in a second finger operated nut 58 on the stem 46. Therefore, by operating this screw the hemostat blade may be forced forwardly in the fenestra to press the tissues of the tonsil against the abutments 24 and 25.

The hemostat blade is provided with an elongated slot 59. This slot has an enlarged end 60 for a purpose hereinunder detailed.

The cutting or severing knife 61 has a cut-

ting edge 62 which is adapted to be thrust into the slot 27 in the end closure 19 of the fenestra, the marginal edges of this blade operating in the side guide slots 33. The rear portion 63 of the knife is loosely secured to the hemostat blade by providing the blade with a perforation 64 in which fits the pin 65 extending downwardly from the hemostat blade so that on the rearward movement of the hemostat blade the knife blade is moved rearward. It will be noted that as the knife edge extends forwardly of the hemostat edge 52 that the knife cuts the tonsil before the hemostat action is brought into play but the hemostat blade crushes the tonsil immediately after severing.

immediately after severing.

The clamping blade 66 is the bottommost blade of the set. This blade is formed quite thin on a straight portion 67 which slides in the side guide grooves 33. Such blade has a vertical end edge 68 which bears against the vertical surface 28 of the end closure 19 of the fenestra. This blade is provided with a downwardly curved portion 69, this having a slot 70 therein. Such blade is attached to a block 71 which has a tooth 72 at its lower forward edge. A stem 73 is connected to the block, which stem extends through the perforation 39 immediately above the handle 14. The end of the stem has a knob 74 to allow pressure by the thumb for thrusting this clamping blade forwardly to clamp the tonsil. The tooth 72 engages in the teeth or serrations 38 and prevents retraction of such blade.

40 A safety device which provides a positive lock for the cutting blade and prevents the use of this until the fixing blade has engaged the tonsil is by the provision of the pin 76 (note Figs. 4 and 5). This pin has a knob 77 at the bottom, an enlarged collar 78, a contracted stem portion 79, a larger cylindrical upper portion 80, and is threaded at the top 81, on which end a nubbed nut 45 82 is threaded. This pin when in its lowered position fits in the slot 34 of the bar 12, the collar 78 preventing its forward movement. It extends through the slot 70 in the clamping blade 66 and extends through the 50 slot 59 and the enlarged portion 60 of the hemostat blade. The enlarged section 80 is of sufficient diameter that it will not permit sliding of the knife blade in a forward direction on account of the section 80 being too 55 great a diameter to operate in the slot 59. The pin is thrust forwardly with the fixing blade being engaged at the upper portion in the perforation 48 when this fixing blade is thrust in by the thumb engaging end 47. 60 However, the adjustment of the hemostat blade and the knife by means of the thumb nut 58 is such that the end of the fixing blade must engage the rim 23 but the enlarged part 35 of the slot 34 in the bar 12 allows 65 the pin 76 to be thrust upwardly by pressure

on the head 77. When in this position the collar 78 may be thrust in with the enlarged portion 35 of the slot 34 and this raises the enlarged cylindrical portion 80 above the slot 59 and allows the hemostat blade with the knife to be thrust forwardly toward the closure end of the fenestra by means of the finger nut 58. It will, therefore, be seen that I have provided a safety factor in that the knife cannot be brought into operation until after the tonsil has been engaged by the fixing blade, and when this hemostat blade and the knife are forced forwardly the knob 74 is pressed, thus thrusting the clamping blade forward to engage the closure end 19 of the fenestra. Thus the tonsil is gripped by this clamping blade and may be held while the knife, the hemostat blade, and the fixing blade are retracted.

As above mentioned, to simplify the device, certain of these blades may be combined, and in Fig. 7 I show a combined hemostat and cutting blade designated by the assembly number 83. This has a blade shank 84, a cutting blade 85 in alignment with this shank and having a cutting edge 86. The sides of this blade operate in the lower groove 33. Secured to one side of this blade there is a block 87 forming the hemostat blade. This has a front edge 88 which is shaped to bear against the surfaces 24 and 25 of the closure end 19 of the fenestra or such edge is shaped to engage the end surface of the instrument should this be changed. With this construction the hemostat and cutting blade are thus formed integral, thus simplifying the construction and, to a certain extent, the operation of the device.

In Figs. 8 and 9 I illustrate a combined fixing and hemostat blade designated by the assembly number 89. In this case there is a heavy blade shank 90 having the fixing blade edge 91 on the top. This blade projects beyond the hemostat face 92 of the hemostat portion 93 of the blade. A pair of side fins 94 are provided, these side fins being guided in the upper guide groove 32 and the hemostat blade fitting between the ribs 30. The face 92 of the hemostat blade is shaped to conform to the end of the instrument so that as the fixing blade is brought into operation to engage and fix the tonsil the hemostat blade is also used to crush the tissues. 105 110 115

In Fig. 6 I show a modified construction in which a snare 95 is utilized. This snare has side wires 96 and an end wire 97. Such end wire when in the operative position is accommodated in the slot 27. When using the snare I prefer to have the combined hemostat and fixing blade 89, this being illustrated in Fig. 6, and also the clamping blade 66 so that the tonsil may be gripped between the fixing blade and the clamp and crushed by the hemostat blade before a tension is placed

on the wires 96, which may be done in any suitable manner so that the end wire 97 is pulled through the tonsil. In this construction the snare is connected to a thumb nut on the stem 46 to exert a pull instead of a thrust.

The clamping blade may be, if desired, automatically retracted in pulling back on the fixing blade by the stem portion 79 of the pin 76 engaging the end of the slot 70 in the curve portion 69 of the clamping blade 66.

The technique in handling my instrument is substantially as follows:

The forward end of the instrument is pressed deeply into the tissues between the tonsil and the posterior pillar. The instrument is manipulated to force the end of the instrument against the tissues attached to the tonsil. The retraction of the end of the instrument acts to pry the tonsil out of its bed and to bulge the tonsil outward. The specially provided and devised fixing blade is now pressed forward between the bulging tonsil and the anterior pillar to further dislodge, lift and shell the tonsil out, into and through the fenestra of the instrument. As the blade goes forward the tissues attached to the tonsil are fixed in the forward end of the instrument. The tissues so fixed are now locked in the fixing device by turning the posterior wheel attached to the fixing blade to the left to force it very tightly against the frame of the instrument.

Having the tissues attached to the tonsil firmly fixed in the end of the instrument, a second blade herein described as a clamping blade is pressed forward to clamp a portion of the tonsil or the tissues to which it is attached to support the tissues and to obviate the necessity of grasping the tonsil with forceps after it has been severed to remove it from the throat. The ratchet device automatically locks the clamping blade.

The tissues now lying between the clamping devices are thoroughly crushed to prevent hemorrhage and are to be severed. This part of the operation is accomplished by the instrument as herein shown in a completely assembled instrument by turning the wheel attached to the hemostat blade to the right.

As the knife blade is connected to the hemostat blade its cutting edge goes forward to sever the tonsil from its attachments but as the blade goes farther forward the hemostat comes into play to crush the tissues. After the knife has severed the tissues the ends of the blood vessels slightly retract and the hemostat acts to crush the ends of the blood vessels to close the lumen of the vessels to prevent bleeding. Before the hemostat blade with the knife blade attached to it can be forced forward to sever and to crush the tissues the safety device if it does not readily drop in place to permit the blade to be forced forward may be slightly pressed upon to free the action of the hemostat blade.

After the tonsil has been severed and the tissues which have been attached to it thoroughly crushed, the hemostat and knife blade should be retracted to its former position by turning the wheel attached to it to the left. This manipulation will release the safety device so that it will fall in place or may be slightly pressed upon to permit the fixing blade to be retracted from its locked position and the instrument removed from the throat.

It will be seen from the above description of the instrument together with the drawing that I have provided a new and important device in what I may call the fixing portion of the instrument, this portion being composed of a specially devised end of the instrument to assist in lifting the tonsil from its bed, and in the specially provided and constructed fixing blade, the forward end of which fixing blade is designed to cooperate with the up-turned part of the end of the frame at the end of the fenestra. These instrumentalities, together with the arrangement for crushing and severing, provide an improved manner in which the faecal tonsil may be dislodged from its bed in the sinus tonsillaris, crushed and severed in a bloodless operation. It is believed that with my improved instrument and in the manner in which it is used that a radical advance has been made in the surgery of the removal of the faecal tonsil.

The closure end 19 of the fenestra of the instrument above the thin rim 23 is provided with a slight upward projection at 23' which extends slightly above the upper plane of the instrument and above the upper side rims 29. This is adapted to act as a pry when pressed between the faecal tonsil and the posterior pillar of the throat to dislodge the tonsil from its bed and help to introduce the tonsil into and through the fenestra of the instrument.

Various changes may be made in the details of construction without departing from the spirit or scope of the invention as defined by the appended claims.

I claim:

1. A surgical instrument having a frame with a fenestra, a slidably mounted fixing blade adapted to engage and free a tonsil, a slidably mounted hemostat blade to crush the tissues, and a slidably mounted means to sever the tonsil.

2. A surgical instrument having a frame with a fenestra, a slidably mounted fixing blade to engage and free a tonsil, a slidably mounted hemostat blade to crush the tissues, a slidably mounted clamping blade to engage the tonsil, and a slidably mounted severing means to sever the tonsil.

3. A surgical instrument as claimed in claim 2, a locking means interconnecting the fixing blade and the severing means to pre-

- vent operation of the severing means before operation of the fixing blade.
4. A surgical instrument having a fenestra, a slidably mounted fixing blade to engage and free a tonsil, a slidably mounted severing means, and a positive locking device interconnecting the fixing blade and the severing means to prevent operation of the severing means until the fixing blade has engaged the tonsil.
5. A surgical instrument having a fenestra, a slidably mounted fixing blade to engage a tonsil, a slidably mounted hemostat blade to crush the tissues, a slidably mounted severing means, a locking device interconnecting the fixing blade and the severing means to prevent operation of the severing means until the tonsil is engaged and gripped by the fixing blade.
6. A surgical instrument as claimed in claim 5, having in addition a slidably mounted clamping blade to clamp the tonsil.
7. A surgical instrument having a frame with a fenestra, a slidably mounted fixing blade to engage a tonsil, a slidably mounted hemostat blade, a severing blade, and means interconnecting the hemostat blade and the severing blade to cause said blades to act together.
8. A surgical instrument as claimed in claim 7, a locking means interconnecting the fixing blade, the hemostat and the severing blade to prevent operation of the hemostat and severing blade until the tonsil has been engaged and gripped by the fixing blade.
9. A surgical instrument having a frame and a fenestra, a slidably mounted fixing blade to engage and retain a tonsil, a slidably mounted hemostat blade, a slidably mounted severing blade, the hemostat blade and the severing blade being rigidly attached together.
10. A surgical instrument having a frame and a fenestra, a slidably mounted fixing blade to engage and retain a tonsil, a slidably mounted hemostat blade, a slidably mounted severing means, the fixing blade and the hemostat blade being rigidly connected together.
11. A surgical instrument having a frame with a fenestra, a slidably mounted hemostat blade, a slidably mounted clamping blade, and a slidably mounted severing means positioned intermediate between the hemostat and the clamping blade.
12. A surgical instrument having a frame and a fenestra, a slidably mounted fixing blade to engage and retain a tonsil, a slidably mounted hemostat blade, a slidably mounted severing blade, the hemostat blade and the severing blade being rigidly attached together, and a locking means interconnecting the fixing blade and the combined hemostat and severing blade to prevent operation of such latter blade until the tonsil has been engaged and gripped by the fixing blade.
13. A surgical instrument as claimed in claim 9, a clamping blade slidably mounted on the side of the combined hemostat and severing blade opposite to that of the fixing blade and being adapted to clamp the tonsil.
14. A surgical instrument having a frame and a fenestra, a slidably mounted fixing blade to engage and retain a tonsil, a slidably mounted hemostat blade, a slidably mounted severing blade, the hemostat blade and the severing blade being rigidly attached together, a locking means interconnecting the fixing blade and the combined hemostat and severing blade to prevent operation of such latter blade until the tonsil has been engaged and gripped by the fixing blade, a clamping blade slidably mounted on the side of the combined hemostat and severing blade opposite to that of the fixing blade and being adapted to clamp the tonsil.
15. A surgical instrument having a frame and a fenestra, a slidably mounted fixing blade to engage and retain a tonsil, a slidably mounted hemostat blade, a slidably mounted severing means, the fixing blade and the hemostat blade being rigidly connected together, and a locking device interconnecting the combined fixing blade and hemostat blade and the severing means to prevent operation of the severing means until the fixing blade has engaged the tonsil.
16. A surgical instrument as claimed in claim 10, having in addition a clamping blade on the opposite side of the severing means to that of the combined fixing and hemostat blades and slidably mounted in the frame to have its operative end slide in said fenestra.
17. A surgical instrument having a frame and a fenestra, a slidably mounted fixing blade to engage and retain a tonsil, a slidably mounted hemostat blade, a slidably mounted severing means, the fixing blade and the hemostat blade being rigidly connected together, and a locking device interconnecting the combined fixing blade and hemostat blade and the severing means to prevent operation of the severing means until the fixing blade has engaged the tonsil, and having in addition a clamping blade on the opposite side of the severing means to that of the combined fixing and hemostat blades and slidably mounted in the frame to have its operative end slide in said fenestra.
18. A surgical instrument having a frame with a fenestra, a slidably mounted fixing blade, a slidably mounted severing means, the fixing blade having a perforation therethrough, the severing means having an elongated slot and the frame having an elongated slot, each with enlargements at one end, the pin having an enlarged collar fitting in said perforation and adapted to extend into the enlargement of the slot in the severing means, said pin also having an enlarged collar adjacent its lower end to prevent up-

ward movement of said pin except when in alignment with the enlargement of the slot in the frame, said pin having a section of reduced diameter to slide in the contracted portion of the slots in the severing means and in the frame.

19. A surgical instrument having a frame with a fenestra, said frame having a lower bar with an elongated slot therethrough, said slot having an enlargement at one end, a slidably mounted fixing blade having a perforation, a slidably mounted severing blade having an elongated slot with an enlargement at one end, a hemostat blade interconnected with the severing blade, a clamping blade having an elongated slot, a locking pin having a relatively small stem portion and enlarged collar adjacent the bottom, and a second enlarged section at the top fitting in said perforation, the contracted portion being adapted to slide in the slots in the severing blade and in the bar of the frame, and the enlarged portion and the collar being adapted to allow upward movement of the pin in the enlarged portions of the slots of the fixing blade and the bar of the frame.

In testimony whereof I have signed my name to this specification.

BURDETTE D. LA FORCE.
